UNITED STATES PATENT OFFICE.

ARCHIE J. GALVIN, OF CLEVELAND, OHIO.

SEWER CONSTRUCTION.

No. 882,940.

Specification of Letters Patent. Patented March 24, 1908.

Application filed March 12, 1906. Serial No. 305,466.

To all whom it may concern:

Be it known that I, ARCHIE J. GALVIN, a citizen of the United States, resident of Cleveland, county of Cuyahoga, and State of Ohio, have invented a new and useful Improvement in Sewer Construction, of which the following is a specification, the principle of the invention being herein explained and the best mode in which I have contemplated applying that principle so as to distinguish it from other inventions.

My invention relates to the construction of conduits for sewer or other purposes out of reinforced concrete.

15 The object of the invention is to provide a form of concrete construction that is adapted for general use in the field indicated, that will permit of rapid erection, and that will present the desirable characteristics of efficiency 20 and durability when erected.

To the accomplishment of these and related objects said invention consists of means hereinafter fully described and specifically set forth in the claims.

25 The annexed drawing and the following description set forth in detail certain mechanism embodying my invention, such disclosed means constituting, however, but one of various mechanical forms in which the 30 principle of the invention may be used.

In said annexed drawing:—Figure 1 represents in perspective a section of a conduit or sewer embodying my improved form of construction, a portion of such conduit having been broken away to better show the details of this construction; Figs. 2, 3 and 4 are respectively a plan view, a side elevation, and an end elevation of the block used to form the bottom of such conduit; Figs. 5, 6 and 7 are respectively a plan view, an end elevation, and a side elevation of the block used to form the top of such conduit; and Figs. 8, 9 and 10 are respectively an end elevation, a side elevation, and a plan view of 45 the blocks designed to form the lateral portions of the said conduit.

Heretofore in the application of reinforced concrete to the construction of sewers, the concrete has in the main been made and applied in the field; the resulting structure being what is termed monolithic in character. As a consequence necessarily entailed by this manner of building, the reinforcing material has also had to be applied in the field. Such 55 material for reasons well understood by those familiar with the art, and hence not

requiring elucidation here, has almost invariably been steel in one shape or another, the purpose of such reinforcing material, being to resist tension stresses, the concrete 60 itself being particularly adapted to withstand compression but without coherence. The steel bars or rods which are ordinarily employed are therefore designed to be embedded in those portions of the conduit that are 65 subjected to the greatest tension. If not properly positioned they are absolutely useless. Now it is evident that, under the conditions that usually maintain in sewer building operations, the proper placing of such 70 bars or rods is more easily calculated than actually secured. For not only are the workmen usually cramped for space, as in a tunnel or trench, but they are more often ignorant and careless, and hence not even 75 the most rigid system of inspection can insure that all the work will be done exactly right.

I am aware that an attempt has been made to remedy these conditions by using molded 80 concrete blocks of a proper shape to give the desired contour to the arch of the conduit. In this case the reinforcing bars have been disposed in outwardly opening grooves formed in the contiguous faces of the blocks. 85 Such bars are designed to be mechanically held in the proper position in such grooves pending their being filled in with mortar and the setting of such mortar. Obviously this system is open to most of the objections enumerated in connection with the monolithic construction. Only by the exercise of great 90 care can the proper placing of the bars be insured, and once in place, there is no way of finding out how the work has been done 95 except by tearing down the structure. Furthermore, the adhesion between the molded blocks and concrete or mortar introduced into the grooves is apt to be poor and so the arch proper is often left without any 100 support whatever.

In my improved system I propose to obviate these several difficulties in a manner that will presently appear. As is evident from an inspection of Fig. 1 of the drawing, 105 I discard the familiar arched form of construction in favor of the rectangular form there shown; and while I do not propose to necessarily limit myself to such rectangular form, I much prefer it, particularly for sewers 110 or conduits of moderate dimensions.

The principle of construction exemplified

in such conduit, whatever its form, is the use therein of separate molded blocks designed to occupy specific positions in the completed structure and having embedded therein, in the process of making, the reinforcing material. This material I dispose in each particular type of block in proper position to fortify such block against the strains to which it will be subjected. Thus I construct the rectangular sewer illustrated of blocks respectively designed in accordance with this principle to form the bottom, sides, and top of the sewer. The bottom blocks A are of substantially the form shown in Figs. 2, 3 and 4, i. e. of a general rectangular shape with a central longitudinal depression a and longitudinal grooves or recesses a' along its sides. Embedded transversely in the block and near its upper surface are reinforcing members a^2 in the form of steel bars or rods, preferably having their ends bent downwardly for the purpose of anchorage.

The lateral blocks B, Figs. 8, 9 and 10, are likewise of substantially rectangular form, and are designed to stand with their lower ends registering in the recesses a' in the sides of the bottom blocks A. Such side blocks have embedded in them reinforcing members b similar to members a^2 . These are however vertically disposed and lie near the inner faces of the blocks. The vertical edges of the blocks are furthermore beveled as plainly appears in Fig. 10, whereby a triangular or wedge-shaped space b' is formed between contiguous blocks. The blocks are preferably disposed so as to bring this space on the inner face of the side wall, Fig. 1. By virtue of this construction it is seen that the blocks may be positioned first and the mortar applied between them afterwards with assurance that a good joint will be secured. The mortar space may just as well be on the outside as inside except that ordinarily the outside of the wall would not be so readily accessible. No such mortar space is deemed necessary for blocks A for the reason that they lie solidly on the ground at the bottom of the ditch or tunnel and hence the mortar can be applied in the customary manner.

The top of the conduit is formed of blocks C, Figs. 5, 6 and 7. These blocks are designed to be placed transversely of the conduit and are provided with longitudinal grooves or recesses c' along their sides, similar to recesses a' in blocks A, designed to engage the upper ends of the lateral blocks B. Reinforcing members c are embedded in the blocks in a transverse position and near the block's under face. The transverse edges of these top blocks are given a bevel similar to that given the vertical edges of the side blocks so that when in place a wedge-shaped mortar space c^2 is formed between contiguous blocks and on the outside of the conduit, Fig. 1. The advantage of this space in facil-

tating the perfect closure of the joints between such blocks is at once apparent.

As I make the blocks just described in a plant or factory apart from the sewer building, it is evident that much greater care can be exercised in the mixing of the concrete and particularly in the placing of the reinforcing material than is possible under the trying conditions of field work. Inspection of the finished product may be made in the way that other structural materials are usually tested, i. e. samples chosen at hazard are taken and examined, and the entire lot judged thereby. For laying open sewers it is evident also that the rectangular form of construction illustrated is peculiarly well adapted; it not only is much easier to erect than is the arch form, the use of arch centering being done away with, but proper tamping of the earth about the walls is better insured and by the system of reinforcement used the structure can be made to withstand all strains without waste of material. I have already indicated, however, that my method can be readily modified for the construction of the circular or arched type of sewer by simply changing the form of the blocks. The disposition of the reinforcing steel bars of course must be calculated for each different form of block, regard being had to its particular position in the completed structure and the regions of tension that will then exist. Thus the bars, a , b and c in blocks A, B and C, respectively, are disposed in each case in the part of the block that under the load of superimposed earth will be under the greater tension.

Having thus described my invention in detail, that which I particularly point out and distinctly claim is:

1. A conduit comprising the combination of blocks respectively adapted to form the bottom, sides and top of such conduit, the contiguous edges of said top and side blocks being beveled to form mortar spaces, and said top and bottom blocks having recessed sides adapted to receive the top and bottom edges respectively of said side blocks.

2. A conduit comprising the combination of bottom blocks having a central longitudinal depression and recessed sides, lateral blocks fitted to the recessed sides of said bottom blocks and having their adjoining edges beveled to form mortar spaces on the inside of the conduit, and top blocks having recessed sides fitted to the upper ends of said lateral blocks and having their adjoining edges beveled to form transverse grooves on the outside of the conduit.

3. A conduit comprising the combination of bottom blocks having a central longitudinal depression and recessed sides, lateral blocks fitted to the recessed sides of said bottom blocks and having their adjoining edges beveled to form mortar spaces on the

inside of the conduit, and top blocks having recessed sides fitted to the upper ends of said lateral blocks and having their adjoining edges beveled to form mortar spaces on the outside of the conduit, all of said blocks being formed of concrete and having tension members embedded therein in the process of making.

4. A conduit comprising the combination of bottom blocks having a central longitudinal depression and recessed sides, lateral blocks fitted to the recessed sides of said bottom blocks and having their adjoining edges beveled to form mortar spaces on the inside of the conduit, and top blocks having recessed sides fitted to the upper ends of said lateral blocks and having their adjoining edges beveled to form mortar spaces on the outside of the conduit, all of said blocks being formed of concrete and having reinforcing members embedded therein in their respective regions of tension.

5. As an article of manufacture, a substantially rectangular block for the side wall

of a conduit or like structure, such block having its vertical edges beveled and being formed of concrete with reinforcing material vertically embedded therein near the surface designed to be turned inwardly.

6. As an article of manufacture, a block for the top of a conduit or similar structure, such block having its transverse edges beveled and its sides longitudinally recessed and being formed of concrete with reinforcing material embedded therein.

7. As an article of manufacture, a substantially rectangular block for the top of a conduit or similar structure; such block having its transverse edges beveled and its sides longitudinally recessed and being formed of concrete with reinforcing material transversely embedded therein near the block's lower surface.

Signed by me, this 9th day of March 1906.

ARCHIE J. GALVIN.
